UNITED STATES PATENT OFFICE.

JOHN F. O'CONNOR, OF CHICAGO, ILLINOIS, ASSIGNOR TO WILLIAM H. MINER, OF CHAZY,
NEW YORK.

SIDE BEARING FOR RAILWAY-CARS.

1,305,664.

Specification of Letters Patent. Patented June 3, 1919.

Application filed August 23, 1918. Serial No. 251,074.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

My invention relates to improvements in side bearings for railway cars.

The object of my invention is to provide a simple and efficient side bearing.

In the drawings forming a part of this specification, Figure 1 is a vertical, longitudinal section of a side bearing embodying my invention. Fig. 2 is a cross section taken on line 2—2 of Fig. 1. Fig. 3 is a vertical, longitudinal section illustrating a modification.

Referring to the drawings, the numeral 4 indicates the body bolster of a railway car; 25 5 a truck bolster; 6 a base member or retaining casting, which is provided with flanges 7, suitably perforated as at 8 for the passage of the rivets 9, which secure the retaining casting to the bolster 5. The retaining casting is open at its upper side 10 and carries within it the rocker 11, which is provided with a series, as for instance three, as shown in Fig. 1 of the drawings, of cylindrical, bearing surfaces 12—12 regularly arranged with respect to the center of the rocker. The retaining casting is provided with correspondingly curved surfaces 13—13 and intermediate projections 14—14 forming a wall conforming to the periphery 40 of the rocker. In normal position of the rocker, as illustrated in Fig. 1, one of the cylindrical, bearing faces, indicated at 14, is opposed to the body bolster and is adapted to be engaged thereby. On movement, the 45 rocker travels toward the end of the base member and on extreme travel to one end, as for instance its left end, will assume the position shown by the dotted line 15 in Fig. 1. In this position, or in any position, a

50 portion of the periphery of the rocker will engage the inner wall of the retaining casting, and, on account of the conformation of the said wall and of the rocker, the bearing will, at all times, be of substantially

the same height, and will, on movement 55 away from its normal position, return to its normal position positively after each actuation in either direction from the normal. In the modification shown in Fig. 3, the numeral 20 indicates a bolster with a base 60 member or retaining casting 21 secured thereto, the base casting having within it a rocker 22 provided with a series of cylindrical bearing faces 23, the said bearing faces being five in number, as illustrated in 65 Fig. 3, and the interior wall of the base member being conformed to substantially fit the periphery of the rocker in any actuation from its normal position. Its normal position is shown as midway between the ends of the 70 retaining member and its position upon extreme actuation to the left is shown by the dotted line 24 in Fig. 3. The conformation of the inner wall of the base member and of the rocker serves to positively position the rocker in the same manner as does the structure illustrated in Figs. 1 and 2.

As will be evident from the preceding description and examination of the drawing, my improved anti-friction element is formed 80 by bringing together a plurality of cylindrical sections and merging them in such manner that the axes of the various cylindrical sections coincide with the angles of a regular polyhedron whose own axis or center 85 corresponds to the actual center of my improved anti-friction element. For instance, in Fig. 1, the centers of the three cylindrical sections 12—12 coincide with the three angles of an equilateral triangle whose center is the 90 center of the anti-friction element and in Fig. 3, the centers of the cylindrical surfaces 23 coincide with the angles of a regular pentagon whose center corresponds to the center 95 of the anti-friction element. With this construction, it is evident that the anti-friction element may be turned bodily so as to present different bearing surfaces to thereby minimize wear and prolong the life of the device.

I claim:

1. In an anti-friction bearing, the combination with a housing, of a rocker associated therewith, said rocker comprising a series of merged cylindrical sections having their axes spaced equal distances apart and uniformly located with respect to the axis of the rocker itself, said rocker being adapted 105

to move bodily with respect to the housing and the latter having its interior surfaces conformed to the peripheral surfaces of the rocker.

5 2. As an article of manufacture, a rocker for anti-friction bearings, said rocker comprising a series of merged cylindrical sections, the axes of said cylindrical sections

coinciding with the angles of a regular polyhedron whose own axis coincides with the 10 axis of the rocker.

In witness that I claim the foregoing I have hereunto subscribed my name this 19th day of Aug. 1918.

JOHN F. O'CONNOR.

Copies of this patent may be obtained for five cents each, by addressing the "Commissioner of Patents, Washington, D. C."
